United States Patent

Des. 241,503
Patented Sept. 21, 1976

241,503

INJECTOR SLEEVE REMOVING TOOL

Robert E. Parker and Paul E. Parker, both of 2047 Angel-
crest Drive, Hacienda Heights, Calif. 91745

Filed May 23, 1975, Ser. No. 580,314

Term of patent 3½ years

Int. CL D8—05

U.S. CL D8—51

FIG. 4.

FIG. 1.

FIG. 2.

FIG. 3.

FIG. 1 is a side elevational view of an injector sleeve removing tool showing our new design;

FIG. 2 is a similar view taken at right angles relative to the view of FIG. 1;

FIG. 3 is an underside view of the tool; and

FIG. 4 is a top plan view.

We claim:

The ornamental design for an injector sleeve removing tool, substantially as shown.
